UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

PROCESS OF MAKING STITCH-DOWN SHOES.

1,191,534.

Specification of Letters Patent. Patented July 18, 1916.

Application filed May 21, 1913. Serial No. 768,974.

To all whom it may concern:

Be it known that I, ADAM H. PRENZEL, a citizen of the United States, residing at Halifax, in the county of Dauphin and State 5 of Pennsylvania, have invented certain Improvements in Processes of Making Stitch-Down Shoes, of which the following description, in connection with the accompanying drawings, is a specification, like reference characters on the drawings indicating like parts in the several figures.

This invention relates to processes of making shoes and has for its general object to provide an improved process of manufacturing 5 stitch-down shoes.

Stitch-down shoes, as they have been manufactured up to the present time, may be classified generally as single sole stitch-downs, which cannot be repaired without 10 relasting, and double sole stitch-downs, which have the upper secured to an insole as well as to an outsole and which can therefore be repaired, so far as replacing the outsole is concerned, without relasting. In the 15 manufacture of both kinds of stitch-down shoes, little attention has been paid to the support of the upper upon the inside of the shoe and to the proper shaping of the shoe with the result that stitch-down shoes are 20 generally in disfavor.

One of the objects of the present invention is so to facilitate the making of stitch-down shoes that, without increasing materially the cost of shoes of that type, their 25 appearance, fit and wearing qualities may be improved.

A further object of the invention is to produce a stitch-down shoe which can easily be repaired.

A particular object of the invention is the production of a stitch-down shoe which is especially adapted to be manufactured by the staple lasting process and which, when so manufactured, has substantially every 45 appearance and substantially all the qualities of the best grades of shoes.

The novel shoe produced by the process of the present invention is not claimed herein but forms the subject matter of my co-pending application Serial No. 861,821, filed September 15, 1914, which co-pending application is a division of the present application.

Other objects and important features of

the invention will appear from the following description and claims when considered in connection with the accompanying drawings, in which—

Figure 1 is a perspective view, partly in section, showing the construction of, and the mode of preparing, the insole employed in the manufacture of the shoe of this invention; Fig. 2, by section and elevation, shows the manner of lasting the shoe and of securing the insole to the upper; and Fig. 3 shows, in broken perspective, a completed shoe and, in section, the relative positions of the different parts of the shoe; Fig. 4 shows a cross section of the insole.

In order that the shoe may be resoled 70 without relasting, it is essential that the upper be secured to an insole independently of its connection with the outsole. It is important also, in order that the upper may keep its shape as it is worn, that there be 75 provided upon the inside of the upper some support above the point or line where the upper is bent outwardly to form the outwardly flange by which it is secured to the insole and outsole.

To provide an insole to which the upper may be secured independently of its attachment to the outsole and at the same time to provide means for supporting the upper upon the inside and furthermore to provide 85 a shoulder or a crease against which or into which the upper may be forced in the lasting operation is one of the objects of the invention, the invention aiming particularly to provide these elements without increasing materially either the material cost or the labor cost of manufacturing the shoe.

In Fig. 1 is shown the insole provided with the upper supporting means, this insole being preferably formed, as shown in Fig. 1, by providing the usual so-called "extension insole" 2, that is, an insole which will extend to the edge of the outsole, and securing to this extension insole an insole proper 4 which will be of such dimensions 95 and outline that it will substantially fit the bottom face of the last and will lie inside the upper and furnish a shoulder or inside support 6 for the upper.

In order to provide proper insulation of 105 the foot from the ground and also to cushion the foot, a filling piece 8 of felt, felt paper or other suitable material is preferably in-

terposed between the insole proper 4 and the extension insole 2, this piece, as shown in Figs. 1, 2 and 3, being located inside of the stitches 10 by which the insole 4 has been 5 secured to the extension insole 2, although it will be obvious that this piece can extend, if desired, out far enough so that the stitches 10 will pass through it and so that it will tend to separate the two insole parts 10 to open the crease to facilitate the lasting operation. This alternative construction is shown in Fig. 4.

It will be noted that the stitches 10 secure the insole proper 4 to the extension insole 2 15 only in the shank and throughout the forepart. At the heel end the insole 4 is preferably left unattached to the extension insole 2 to furnish a tongue 12 over which the heel end of the upper and the counter may be 20 turned in and lasted down, the lasting tacks being driven through and clenched upon the upper face of the tongue 12. At the point where the inturned and outturned portions of the upper meet, the upper is preferably 25 slit in from its edge in a well-known manner.

The insole, having been prepared in the manner shown in Fig. 1, is placed upon the bottom face of the last so that the edges of 30 the insole proper 4 are substantially flush with the edges of the bottom face of the last. The upper is then placed upon the last, drawn over the edge of the last, forced into the crease between the edge of the insole 35 proper 4 and the upper face of the extension insole 2, and preferably secured to the extension insole 2 by staples 14 driven into the angle of the upper and through the insole 2 and clenched upon the bottom face of 40 said insole 2. This operation may conveniently be performed upon a lasting machine of the type shown in my co-pending application Serial No. 736,079 filed December 11, 1912 upon which were granted 45 United States Letters Patent No. 1,117,440, dated November 17, 1914.

The shoe having been lasted in the manner just described and as shown in Fig. 2, an outsole 13 is placed upon the bottom face 50 of the extension insole 2, the welt 16 is laid upon the outturned flange of the upper, and the welt, upper, extension edge of the extension insole 2 and the outsole are united by 55 stitches 18. The welt 16 and the stitches 18 extend preferably from a point just beyond where the heel end of the upper is lasted in upon one side of the shoe to a similar point upon the other side of the shoe. The heel 20 is then placed upon the heel end of 60 the shoe. The heel end 22 of the extension insole, the heel end of the outsole 13 and the heel are all united by nails driven through these parts and also through the tongue 12 and clenched upon the inside of

the shoe. If desired the heel-seat may be 65 nailed, independently of the nails which secure the heel, before the heel is placed upon the shoe.

From the foregoing description and from the drawings it will be apparent that this 70 shoe may be made with comparatively little labor, that the formation of the insole does not require the use of expensive materials to obtain the most satisfactory results, that all 75 of the operations in the manufacture of the shoe can be performed by the use of machinery, that the parts of the shoe are so confined inside and out that the shoe does not tend readily to lose its shape as it is worn, and that when the outsole is worn 80 through the shoe can easily be repaired since the upper is secured firmly and independently in its lasted position to the insole.

Having described my invention, what I claim as new and desire to secure by Letters Patent of the United States is:—

1. That improvement in the art of making stitch-down shoes which comprises forming an insole by attaching to a sole of the dimensions of the outsole a sole of a size and 85 shape to fit inside the upper, the marginal portion of said smaller sole being left unattached to the larger sole, turning out the lower margin of the upper forcing the angle of the upper between the lower marginal 90 face of the smaller sole and the upper face of the larger sole, permanently attaching the upper in this location, and then uniting an outsole to said upper and insole.

2. That improvement in the art of making 95 stitch-down shoes which comprises forming an insole by attaching to a sole of substantially the dimensions of the outsole a sole of a size and shape to fit inside the upper, the marginal portion of said smaller sole being left unattached to the larger sole, assembling said insole and said upper upon a last, turning out the lower margin of the upper and forcing the angle of the upper between the lower marginal 100 face of the smaller sole and the upper face of the larger sole, permanently securing the upper in the location by staples inserted in said angle and clenched upon the bottom face of the 105 insole, and securing an outsole to said insole and upper.

3. That improvement in the art of making 110 shoes which comprises forming an insole by attaching to a sole of substantially the dimensions of the outsole a sole of a size and 115 shape to fit inside the upper and placing between these two soles before they are united a filling piece, the marginal portion of said smaller sole projecting beyond the edge of said filling piece and being left unattached to the larger sole, turning out the lower margin of the upper, forcing the angle of the upper between the lower marginal

face of the smaller sole and the upper face of the larger sole, permanently securing the upper in this position, placing a welt upon the outturned margin of the upper with its inner edge extending into said angle, and securing an outsole to said welt, upper and insole.

In testimony whereof I have signed my name to this specification in the presence of two subscribing witnesses.

ADAM H. PRENZEL.
